TREATMENT OF HYDROCARBONS

Harrison L. Hays, Bartlesville, Okla., assignor to
Phillips Petroleum Company, a corporation of
Delaware

Application September 2, 1941, Serial No. 409,283

10 Claims. (CL 196—28)

This invention relates to the manufacture of higher octane number hydrocarbons from lower octane number hydrocarbons and in particular to the manufacture of aviation and/or motor fuels of high octane number from a charge stock which may contain any combination of the hydrocarbons in the natural gasoline range in any concentration whatsoever.

The value of the employment of higher octane number hydrocarbons in the operation of internal combustion engines which are designed for their efficient use is well known. It is also well known that olefin hydrocarbons are less likely to cause detonation when used as a fuel than are the corresponding paraffin hydrocarbons. Even among the members of any one series of hydrocarbons, such as the paraffin series, the various individual hydrocarbons differ widely among themselves as to detonation or combustion characteristics. This is exemplified by the detonation properties of normal hexane and 2,2-dimethyl butane (neohexane). Normal hexane, a straight chain hydrocarbon, is known to have an octane number of 59, whereas its isomer 2,2-dimethyl butane or neohexane, a hydrocarbon with a highly branched molecular structure, is generally known to have an octane number rating of 95.

The principal object of this invention is to produce higher octane number normally liquid hydrocarbons from lower octane number normally liquid hydrocarbons such as those found in natural gasoline stocks.

Another object is to produce higher octane number hydrocarbons suitable for use either directly as aviation or motor fuels, or as preparatory materials therefor, utilizing a charge stock which comprises any combination of the hydrocarbons in the natural gasoline range in any concentration whatsoever.

Further objects and advantages of this invention will become apparent as the following description and disclosure proceeds.

A number of methods have been proposed for the manufacture of higher octane number hydrocarbons from those of lower octane number, such as are utilized in the production of isooctane from isobutane and other hydrocarbons by various thermal and catalytic means, etc. However, by means of the present invention, through the use of satisfactory catalysts and suitably selected conditions of temperature and pressure, a feed stock which contains any of the hydrocarbons in the natural gasoline range may be made to react to produce other hydrocarbons of higher octane number suitable for use as or in the preparation of aviation fuels and/or motor fuels.

According to this invention, a natural gasoline feed stock, as heretofore described, is, in the initial step of the process, subjected to catalytic desulfurization wherein pressures and temperatures used are of the order of 0 to 100 pounds per square inch and 500° to 800° F., respectively. A suitable catalyst is employed, such as bauxite impregnated with sodium hydroxide. Conditions are maintained such that decomposition reactions are slight, and less than 5 per cent and preferably less than 2 per cent of the charge stock undergoes splitting reactions. Desulfurization is so conducted that the desulfurization product contains less than about 0.1% of sulfur and preferably less than about 0.01% of sulfur. Actually, pressures and temperatures of the order of 0 to 50 pounds per square inch and 500° to 700° F., respectively, seem to be preferable in promoting the desulfurization reaction in order to suppress more than slight decomposition. Suitable means of separation are now employed, wherein desulfurized hydrocarbons in the aviation fuel range of molecular weights are separated from those of higher molecular weight which are of motor fuel grade. Prior to fractionation, a portion of the total liquid may be recycled to the desulfurization step for the purpose of control.

The fraction of aviation fuel range of molecular weight is subjected in the presence of a suitable isomerization catalyst such as one of the metallic halides, particularly aluminum chloride carried on a satisfactory supporting material and in the presence of hydrogen chloride, to reaction pressure and temperature conditions of the order of 0 to 500 or more pounds per square inch and 0 to 1000° F., respectively. These conditions are maintained such that decomposition reactions are slight, and less than 10 per cent, and preferably less than 5 per cent of the charge stock undergoes splitting reactions. The isomerization reaction is favored considerably if the temperatures which are used in conjunction with a reasonably high pressure are maintained well below those at which appreciable decomposition usually begins. Therefore, pressures and temperatures of the order of 50 to 300 pounds per square inch and 200° to 700° F., respectively, seem to be preferable in promoting the isomerization reaction to be employed in this step of the process.

Following suitable means of separating the fraction of aviation grade from the isomerization product, the fraction of heavier material which is formed during the isomerization reaction is fed to the dehydrogenation step of the process together with hydrocarbons of motor fuel grade from the desulfurization step. This combined

feed together with insufficiently reacted recycle stock from a later stage in the process is subjected in the presence of a suitable catalyst, such as chromic oxide gel, chromic oxide carried on a suitable support, or bauxite, to reaction pressure and temperature conditions of the order of 0 to 100 pounds or more per square inch and 600° to 1200° F., respectively. These conditions are maintained such that not more than 30 per cent of the total feed is converted per pass through the reaction zone. The suitable exact conditions depend upon the type of feed stock and the catalyst used and are best determined by trial. Separation steps are now employed which result in the isolation of the hydrocarbons in the motor fuel range from those both lighter and heavier.

The process of this invention may be carried out in equipment such as that illustrated diagrammatically in the drawing, which portrays one means by which the process may be practiced.

Referring to the drawing in detail, a natural gasoline feed stock as heretofore described is introduced via supply line 1, tank 2, and conduit 3, together with recycle stock coming from separators 10 and 13 by way of conduit 16, under suitable pressure to heating coil 4 enclosed in a suitable furnace or heating means 5. The pre-heated hydrocarbons then pass through conduit 6 into a suitable catalyst case 7, where they are subjected to the influence of a suitable catalyst such as bauxite impregnated with sodium hydroxide. The reaction temperature is such that the decomposition of the hydrocarbons so treated will be not more than 2 per cent by weight for contact periods which may vary from one to two liquid volumes of feed per hour per volume of catalyst, the most suitable exact conditions being determined by trial.

Following passage through the reaction zone the hot reaction products exchange heat with the cold feed to the isomerization system in heat exchanger 9. Thence they pass via conduit 8 into a cooler where they are lowered to a suitable temperature prior to entry into separation element 10. Here a rough separation is made between components of aviation grade and heavier and lighter components. The aviation and heavier hydrocarbons pass via conduit 11 into separation element 17. The lighter components, which, due to the rough separation, may contain desirable components, are pumped via conduit 12 through suitable cooling and condensing means into separation element 13. Thence the light, undesirable components are removed from the system through conduit 14. The pressure in element 13 is such that the condensate therein comprises the major portion of the desirable components in the overhead stream from element 10. The condensate in 13 passes out via conduit 15 and joins the normal feed to separation element 17 which is passing through conduit 11. For control, a portion of the feed to element 17 may be recycled to tank 2 via conduit 16. A separation is secured in element 17 such that the desirable lighter components of essentially aviation grade molecular weight pass through conduit 18 in which they are cooled and condensed into condensate accumulator 19. A portion of the condensate in accumulator 19 is compressed to a sufficiently high pressure and is introduced as a reflux or cooling medium near the top of 17 via conduit 20. The condensate in 19 in excess of that required for this purpose passes from 19 via isomerization feed conduit 22. In order to enable withdrawal of a portion of the desulfurized

condensate in 19 from the system for use as or in the blending of aviation gasoline, should such withdrawal be desired, conduit 21 is provided in communication with conduit 22. The condensate in excess of that required for refluxing and withdrawal as aviation fuel comprises the feed to the isomerization step.

The raw feed to the isomerization step passes via conduit 22, together with recycle stock from conduit 41, into isomerization feed surge tank 23. From 23 the total feed passes via conduit 24, during which it is compressed to a suitable isomerization reaction pressure of between 0 and 500 or more pounds per square inch, through heat exchanger 9, where it exchanges heat with the hot desulfurization catalyst chamber effluent in order to obtain a satisfactory isomerization reaction temperature. Conduit 25 provides a by-pass around heat exchanger 9 through which a portion of the isomerization feed may be passed for the purpose of controlling its temperature. The preheated feed stock then passes, together with light hydrocarbon vapors and hydrogen chloride recycle via conduit 48, into a suitable isomerization catalyst case 26. In the catalyst case 26 the gasoline hydrocarbons are subjected to the influence of a suitable catalyst, such as one of the metallic halides, aluminum chloride, for example. Instead of aluminum chloride, other amphoteric metal halides capable of acting as isomerization catalysts may be employed. Preferably, an aluminum halide is used, such as aluminum chloride or aluminum bromide, etc. The reaction temperature is so regulated that the decomposition of the hydrocarbons so treated will be less than 5 per cent by weight for reaction periods which may vary from about 5 to 30 minutes, the most suitable exact conditions being determined by trial. Conditions may be maintained to vary the composition of the equilibrium mixture of reaction products in accordance with the type of product desired. The hydrogen halide employed in this isomerization step preferably corresponds to the metallic halide isomerization catalyst. The hydrogen halide serves to activate the isomerization catalyst.

Following passage through the reaction zone, the hot reaction products pass via conduit 27 into a suitable cooler 28 where they are cooled by suitable means prior to being pumped into separation element 30. Conduit 29 comprises a by-pass around cooler 28 for the purpose of temperature control. Hydrocarbons lighter than those desired in aviation fuel, together with hydrogen chloride, pass through conduit 31, in which they are cooled and condensed, into condensate accumulator 32. A portion of the condensate from accumulator 32 is compressed to a pressure sufficiently high to permit its introduction as a reflux or cooling medium near the top of element 30 via conduit 33. The condensed portion in excess of that required for this purpose is continuously removed from the system as a liquid through conduit 34. The uncondensed portion which contains propane and lighter hydrocarbons and an appreciable concentration of hydrogen chloride is removed as a vapor near the top of element 32 and passes via conduit 48 to its point of juncture with the hot isomerization catalyst chamber feed in conduit 24. This material is recycled only because of its hydrogen chloride content. If operating conditions render it desirable, a portion of this uncondensed material may be vented from conduit 48 by suitable venting means. A pump 49 may be provided in

conduit 48 for compressing the returned material depending upon the desired operating pressure of the isomerization catalyst case 26. Fresh hydrogen chloride make-up is provided by hydrogen chloride gas storage tank 50.

The bottom product from separation element 30, which contains the valuable aviation fraction, together with insufficiently reacted material and some heavier hydrocarbons which were formed in the reaction zone, passes via conduit 35 through a neutralization contactor 36 where a material such as an aqueous caustic soda solution is employed for the purpose of neutralizing or removing the small quantity of hydrogen chloride contained therein. Thence the hydrocarbons and neutralizing solution pass into a settling tank 37 where the hydrocarbons are separated from the neutralizing solution and pass via conduit 41 into separation element 42. The partially used neutralization solution which is recovered in settling tank 37 may be recirculated via conduit 38. Fresh neutralizing solution is introduced via conduit 39 and spent solution is withdrawn from the system via conduit 40.

The aviation fuel constituent from separation element 42 passes via conduit 43, in which it is cooled and condensed, into condensate accumulator 44. As in the preceding separation step, a portion of this condensate is compressed and introduced via conduit 45 near the top of element 42 to act as a reflux or cooling medium. The valuable constituent in excess of the amount required for refluxing purposes is removed from the system via conduit 46. This material may serve as, or be employed in the blending of, aviation gasoline. A portion of this material, however, is recycled to the system via conduit 47 for reaction control. The bottom product from element 42, which comprises hydrocarbons of higher molecular weight, passes via conduit 51, together with dehydrogenation raw feed from the desulfurization system which is passing via conduit 52, into dehydrogenation system feed tank 53, where it mingles with dehydrogenation recycle stock entering tank 53 via conduit 54.

The combined feed to the dehydrogenation system passes from tank 53 via conduit 55 in which it is compressed to a suitable reaction pressure between 0 and 100 or more pounds per square inch, through heat exchanger 56 where a certain temperature is obtained by heat interchange with catalyst chamber effluent products which are passing through conduit 60. Prior to entry into the heat exchanger, the liquid feed is mixed with hydrogen and light hydrocarbon vapors entering through conduit 61. The partially heated feed then passes through a heating coil 57 which is enclosed in a suitable furnace or heating means. The preheated hydrocarbons (600° to 1200° F.) then pass via conduit 58 into a suitable dehydrogenation catalyst case 59 where they are subjected to the influence of a suitable dehydrogenation catalyst, such as one of those heretofore described. The reaction temperature is such that the dehydrogenation of the hydrocarbons so treated will not be more than 30 per cent by weight for reaction periods corresponding to flow rates which may vary from 1½ to 3 volumes of liquid feed per volume of catalyst per hour, most suitable exact conditions being determined by trial.

Following passage through the reaction zone the hot reaction products pass via conduit 60 in which they are cooled by a suitable means from the reaction temperature down to a temperature

of the order of 600° to 800° F. prior to entry into exchanger 56, where they are further cooled by heat interchange with the total cold feed as heretofore described. Thence they are additionally cooled and passed into separation element 62. Hydrogen and lighter hydrocarbons, together with some of the heavier hydrocarbons, pass overhead via conduit 63, in which they are cooled and condensed, into separation element 64. The pressure maintained in the element 64 is such that a satisfactory separation is obtained therein between ethane and lighter hydrocarbons containing hydrogen, and butane and heavier hydrocarbons. These lighter hydrocarbons containing the hydrogen can be continuously removed from the system via withdrawal conduit 65. However, it has been found to be essential for proper control of the dehydrogenation reaction to recycle a certain portion of this stream containing hydrogen through conduit 61. The bottom product from separation element 62 passes via conduit 66 in which it is compressed to a pressure sufficiently high to permit its entry, together with the bottom product from separation element 64, into separation element 67. Hydrocarbons which are essentially butane in composition pass overhead via conduit 68, and are cooled, condensed and passed into condensate accumulator 69. A portion of the condensate in 69 is introduced near the top of 67 as a reflux or cooling medium via conduit 70, in which it is compressed sufficiently. The quantity in excess of that required for refluxing is continuously withdrawn from the system through conduit 71 and comprises essentially butane. The bottom product from separation element 67 passes through conduit 72 into separation element 73 where the motor fuel fraction is isolated from hydrocarbons of higher molecular weight. The motor fuel fraction passes through conduit 74, in which it is cooled and condensed, into condensate accumulator 75. A portion of the condensate is taken from accumulator 75 through conduit 76 and compressed to a pressure sufficiently high, and introduced as a reflux or cooling medium near the top of 73. The motor fuel fraction in excess of that required for refluxing is removed from the system via conduit 77. However, it is considered to be necessary to recycle a portion of this material via conduit 54 for process control, particularly to control the quality and yield of desirable materials.

The advantages of the process of the present invention are numerous. The process greatly increases both the octane number and lead response of the hydrocarbons treated. Moreover it enables the ready and economical production of exceedingly high quality fuels of both aviation and motor grades in a single unitary plant. It allows the utilization of cheap and relatively inferior natural gasoline stock for the production of superior aviation and motor gasolines and blending stocks for use in preparing aviation fuel and motor fuel. The desulfurization of the feed stock before catalytic isomerization and before catalytic dehydrogenation is peculiarly beneficial from the standpoint of the adverse effect of sulfur upon the isomerization and dehydrogenation catalysts even in concentrations as low as 0.004 per cent. The present invention allows the ready maintenance of total sulfur content of the feed at a value sufficiently low to insure an economic catalyst life. Moreover the process is advantageous in that it allows the use of ordinary car-

bon steel in the fabrication of the equipment, particularly in that portion of the apparatus employed after the desulfurization step, except in operating zones where temperatures of 1000° F. or higher compel the use of alloy steels of adequate creep stress characteristics. It has been found that sulfur compounds in appreciable concentrations cause severe corrosion of ordinary steel equipment, thereby forcing the using of expensive chromium-containing corrosion-resistant steels. With the process of the present invention this difficulty is readily overcome. Accordingly, the apparatus used in carrying out the process may be inexpensively constructed and has a longer useful life, and the necessity for frequent shutdown of the plant due to corrosion is eliminated.

Another advantage is that, using the process of the present invention, it is not necessary to carry the entire charge through the three major steps, but on the contrary the aviation portion of the isomerization product is adapted directly for use as a superior aviation fuel. The heavy portion of the isomerization product has been largely isomerized to branch chain hydrocarbons and thereby converted to a form where, upon dehydrogenation, it yields a superior motor fuel. With the process of the present invention the heavy portion of the desulfurization product is not subjected to the isomerization step, but goes directly to the dehydrogenation step, which is further advantageous. In addition the process is capable of a high degree of flexibility of operation and of ready control to meet the needs of the original charge stock and the existing demand. The process yields a maximum of premium products from the charge stock at hand in a conveniently controlled economical manner. Moreover the several steps of the process are so inter-related with respect to each other as to give unusual facility of operation and a high degree of operating efficiency.

It will be understood that the embodiment described herein, while representing the preferred practice of my invention now known to me, is merely illustrative of the inventive thought, and that the invention is to be taken as limited only by the spirit and terms of the appended claims.

I claim:

1. A process of producing high octane aviation and motor fuel from relatively low octane number hydrocarbons which comprises subjecting low octane number natural gasoline charge stock to catalytic desulfurization over a solid catalyst and at a temperature of from about 500° to about 800° F., separating the product to recover a fraction in the aviation fuel range of molecular weights, subjecting said fraction to catalytic isomerization, fractionally distilling the isomerization product to recover therefrom a lighter fraction suitable as aviation gasoline and a heavier fraction, subjecting a feed comprising the whole of said heavier fraction to catalytic dehydrogenation, and recovering high octane number motor fuel from the dehydrogenated product.

2. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization, separating the product to recover a fraction suitable as aviation gasoline

and a heavier fraction, combining said heavier fractions, subjecting said combined fractions to catalytic dehydrogenation, and recovering high octane number motor fuel from the dehydrogenated product.

3. A process of producing high octane number hydrocarbons which comprises subjecting relatively low octane number natural gasoline charge stock to catalytic desulfurization, separating the product to recover a fraction in the aviation fuel range of molecular weights and a heavier fraction, subjecting said first-named fraction to catalytic isomerization, separating the product to recover a fraction suitable as aviation gasoline and a heavier fraction, combining said heavier fractions, subjecting said combined fractions to catalytic dehydrogenation, and recovering high octane number motor fuel from the dehydrogenated product.

4. A process of producing high octane number hydrocarbons from relatively low octane number hydrocarbons which comprises subjecting relatively low octane number hydrocarbon charge stock to catalytic desulfurization by passing it under a pressure of from 0 to about 50 pounds per square inch and at a temperature of from about 500° to about 700° F. in contact with a catalyst of bauxite impregnated with sodium hydroxide under conditions such that less than about 2 per cent of the charge stock undergoes splitting reactions during the desulfurization step, separating the product to recover a fraction in the aviation fuel range of molecular weights and a heavier fraction, subjecting said first-named fraction to catalytic isomerization, separating the product to recover a fraction suitable as aviation gasoline and a heavier fraction, combining said heavier fractions, subjecting said combined fractions to catalytic dehydrogenation, and recovering high octane number motor fuel from the dehydrogenated product.

5. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization in the presence of a metallic halide, separating the product to recover a fraction suitable as aviation gasoline and a heavier fraction, combining said heavier fractions, subjecting said combined fractions to catalytic dehydrogenation, and recovering high octane number motor fuel from the dehydrogenated product.

6. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization in the presence of aluminum chloride and in the presence of hydrogen chloride, separating the product to recover a fraction suitable as aviation gasoline and a heavier fraction, combining said heavier fractions, subjecting said combined fractions to catalytic dehydrogenation, and recovering high octane number motor fuel from the dehydrogenated product.

7. A process of producing high octane number hydrocarbons from relatively low octane number hydrocarbons which comprises subjecting rela-

tively low octane number hydrocarbon charge stock to catalytic desulfurization, separating the product to recover a fraction in the aviation fuel range of molecular weights and a heavier fraction, subjecting said first-named fraction to catalytic isomerization under a pressure of from about 50 to about 300 pounds per square inch and at a temperature of from about 200 to about 700° F. in the presence of aluminum chloride and in the presence of hydrogen chloride under such conditions that less than about 5 per cent of the feed undergoes splitting during the isomerization step, separating the product to recover a fraction suitable as aviation gasoline and a heavier fraction, combining said heavier fractions, subjecting said combined fractions to catalytic dehydrogenation, and recovering high octane number motor fuel from the dehydrogenated product.

8. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization, separating the product to recover a fraction suitable as aviation gasoline and a heavier fraction, combining said heavier fractions, subjecting said combined fractions to catalytic dehydrogenation by passing same under a pressure of from 0 to about 100 pounds per square inch and at a temperature of from about 600 to about 1200° F. in contact with a dehydrogenation catalyst selected from the group consisting of chromic oxide gel, supported chromic oxide and bauxite, under conditions such that not more than about 30 per cent of the total dehydrogenation feed is converted per pass through the dehydrogenation reaction zone, and recovering high octane number motor fuel from the dehydrogenated product.

9. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization in the presence of a metallic chloride and in the presence of hydrogen chloride, separating the isomerization product into a first fraction comprising hydrocarbons lighter than those suitable for use in aviation fuel together with hydrogen chloride, a second fraction suitable as aviation gasoline, and a heavier fraction, recycling said first fraction containing hydrogen chloride to the isomerization feed, combining said heavier fractions, subjecting said combined fractions to catalytic dehydrogenation, and recovering high octane number motor fuel from the dehydrogenated product.
10. A process of producing high octane number hydrocarbons from relatively low octane number hydrocarbons which comprises subjecting relatively low octane number hydrocarbon charge stock to catalytic desulfurization, separating the product to recover a fraction in the aviation fuel range of molecular weights and a heavier fraction, subjecting said first-named fraction to catalytic isomerization, separating the product to recover a fraction suitable as aviation gasoline and a heavier fraction, combining said heavier fractions, subjecting said combined fractions to catalytic dehydrogenation, separating the dehydrogenation product into a fraction of high octane number hydrocarbons of motor fuel grade and into a fraction containing hydrogen, and recycling at least a portion of said last-named hydrogen-containing fraction to the dehydrogenation step.

HARRISON L. HAYS.
